FIG. 1

FIG.5

FIG.2

FIG.3

FIG.4

FIG. 1 is a perspective view of a calculator showing my new design;

FIG. 2 is a top plan view thereof;

FIG. 3 is a side elevational view thereof;

FIG. 4 is a front elevational view thereof; and

FIG. 5 is a rear elevational view thereof.

The side of the calculator which is not shown is substantially identical to the side which is shown in FIG. 3.

It is a characteristic feature of the present invention that it includes a keyboard having a group of operating keys of square shape adjacent the left edge thereof, a group of round keys adjacent the right edge thereof, and two intermediate groups of keys including a group of round keys adjacent the square keys at the left of the board and a group of square keys adjacent the round keys at the right of the board.

I claim:

The ornamental design for a calculator, as shown and described.
